CLAIM

The ornamental design for a vehicle wheel, toy vehicle wheel, and/or replicas thereof as shown and described.

DESCRIPTION

This application contains subject matter related to the following co-pending U.S. design patent applications:

Application Ser. No. 29/914,793, filed Oct. 23, 2023 and entitled “Vehicle Wheel, Toy Vehicle Wheel, and/or Replicas Thereof;” and

Application Ser. No. 29/898,105, filed Jul. 24, 2023 and entitled “Vehicle Wheel, Toy Vehicle Wheel, and/or Replicas Thereof.”

FIG. 1 is a perspective view of a vehicle wheel, toy vehicle wheel, and/or replicas thereof according to the design;

FIG. 2 is an additional perspective view thereof;

FIG. 3 is an additional perspective view thereof;

FIG. 4 is a front elevation view thereof; and,

FIG. 5 is a side elevation view thereof.
